UNITED STATES PATENT OFFICE

120,867

DESIGN FOR A COMBINATION MONEY AND TICKET HOLDER

Harold J. Lyon, Los Angeles, Calif.

Application December 20, 1939, Serial No. 89,041

Term of patent 3½ years

To all whom it may concern:

Be it known that I, Harold J. Lyon, a citizen of the United States and a resident of the city of Los Angeles, in the county of Los Angeles, and State of California, have invented a new, original, and ornamental Design for a Combination Money and Ticket Holder, of which the following is a specification, reference being had to the accompanying drawing, forming part thereof.

In the drawing:

Fig. 1 is a front elevational view of the combination money and ticket holder showing my new design.

Fig. 2 is a rear elevational view thereof.

Fig. 3 is a side elevational view thereof.

Fig. 4 is a fragmentary view on a slightly smaller scale, showing the inside of the bag with the handles broken away for convenience of illustration.

Fig. 5 is a bottom plan view thereof.

I claim:

The ornamental design for a combination money and ticket holder, substantially as shown and described.

HAROLD J. LYON.
